(57) **CLAIM**

The ornamental design for a swivel clamp fitting, as shown and described.

DESCRIPTION

FIG. 1 is a front perspective view of the swivel clamp fitting showing my new design;

FIG. 2 is a back perspective view thereof;

FIG. 3 is a right side elevational view of the swivel clamp fitting;

FIG. 4 is a left side elevational view thereof;

FIG. 5 is a front elevational view of the swivel clamp fitting;

FIG. 6 is a top elevation view of the swivel clamp fitting; and,

FIG. 7 is a bottom elevational view thereof.

In all figures, the broken lines showing the tube on which the swivel clamp fitting is used, is for illustrative purposes only and forms no part of the claimed design.
